CLAIM

The ornamental design for an IP telephone, as shown and described.

DESCRIPTION

FIG. 1 is a perspective view of an IP telephone showing my new design;

FIG. 2 is a front view thereof;

FIG. 3 is a rear view thereof;

FIG. 4 is a left side elevational view thereof;

FIG. 5 is a right side elevational view thereof;

FIG. 6 is a top view thereof; and,

FIG. 7 is a bottom view thereof.

The broken line showing of environmental structures is for illustrative purposes only and forms no part of the claimed design.
